United States Patent Office.

JULES F. PAGES, OF SAN FRANCISCO, CALIFORNIA.

Design No. 4,296, dated August 16, 1870.

DESIGN FOR A HAND-STAMP.

The Schedule referred to in these Letters Patent and making part of the same.

To all whom it may concern:

Be it known that I, JULES F. PAGES, of the city and county of San Francisco, State of California, have invented a Design for Seal-Stamp; and I do hereby declare the following description and accompanying drawing are sufficient to enable any person skilled in the art or science to which it most nearly appertains, to make and use my said invention, without further invention or experiment.

My invention relates to a design or figure which I employ as a weight or seal for stamping the impression of any engraving or other characters, which it is desired to imprint upon paper.

In order to more particularly describe my design, reference is had to the accompanying drawing forming a part of this specification, in which—

A represents the base or pedestal. Near one end of this base I cast upon it the legs *a a*, between which the rear end of the body of the figure which serves as a weight is hinged in the usual manner.

The figure or design which I employ is that of the sphinx, having the face of a human, surmounted by a heavy cowl, B. The rear part of the body is that of a lion.

The front paws, *b*, rest under the chin, being cast upon the plate which carries the engraving or other design which it is desired to imprint.

Having thus described my invention,

What I claim, and desire to secure by Letters Patent, is—

The design for a stamp or seal-press above described and shown.

In witness that the above described invention is claimed by me, I have hereunto set my hand and seal.

JULES F. PAGES. [L. S.]
